UNITED STATES PATENT OFFICE.

ULYSSES GRANT LEE, OF CHATTANOOGA, TENNESSEE, ASSIGNEE TO MONTAGUE
MAILING MACHINERY COMPANY, A CORPORATION OF TENNESSEE.

OFFICE ADDRESSING-MACHINE.

1,169,080.

Specification of Letters Patent. Patented Jan. 18, 1916.

Application filed May 22, 1912, Serial No. 769,574. Renewed September 23, 1915. Serial No. 52,283.

To all whom it may concern.

Be it known that I, ULYSSES GRANT LEE, a citizen of the United States, residing at Chattanooga, Tennessee, have invented certain new and useful Improvements in Office Addressing Machines, of which the following is a specification.

My invention relates to the type of addressing machines in which individual address plates are supplied to the printing point beneath a ribbon and the impression is made upon the articles to be addressed by the impact of an impression head, which forces the article downwardly upon the address plate with the ribbon interposed.

In my present machine I employ a hand operated feeding mechanism for the address plates to bring them one after another to the printing point and to carry them away therefrom after making the impression, and a manually operated impression arm carrying the impression arm and having connection to the feeding mechanism to operate the same; a machine of this general type being disclosed in an application for Letters Patent of the United States filed by me July 9th, 1912, No. 703,513. By a machine thus organized either single or multiple impressions can be made from the same address plate, it being entirely within the control of the operator whether or not the address plate shall be discharged from the impression point after making an impression, thus enabling the operator, by simply operating the impression arm, to make any desired number of impressions from the same address plate. Such action is desirable, for instance, in placing addresses upon bills, such as are issued by gas-light or electric-light companies, having one or more coupons or checks attached to the main portion of the bill.

With a machine organized as above described, a fresh portion of the inking ribbon will be brought into use at each operation of the impression arm, the feeding of the ribbon being entirely independent of the feeding of the address plates, this feature also being essential in enabling the operator to make multiple impressions from one address plate.

My present invention concerns particularly the means for feeding the address plates by manually operated mechanism.

My invention further includes an improved form of handle and impression arm for preventing rebound and a double impression from the impression arm.

In the accompanying drawings Figure 1 is a plan view of an address machine embodying my invention. Fig. 2 is a cross sectional view of Fig. 1 substantially on the line 2—2. Fig. 3 is a longitudinal sectional view of Fig. 1 substantially on the line 3—3. Fig. 4 is a sectional view on the line 4—4 of Fig. 2. Fig. 5 is a detail sectional view across the run-way for the address plates adjacent the printing point. Figs. 6 and 7 are views of a combined handle and impression arm, this being a modification of the handle and impression arm of Figs. 1, 2 and 3 and capable of use in place thereof. Fig. 8 is a detail view of a reflector or mirror.

In these drawings 1 indicates a hopper in which the address plates are stored and from which they are moved one by one by projections 2 on an endless chain 3 which passes over an idle roller 4 and about a driving sprocket wheel 5. The projections on the chain engage one depressed margin of the address plates, one of which is indicated in dotted lines at *a* in Fig. 5. These address plates have embossed thereon the type composing the matter or addresses to be printed on the envelope, magazine, or other articles. The address plates move along a run-way composed of the two grooves 6 and 7 of a bar 8 or a portion of the frame, the depressed margins of the address plates being overhung by guard plates 9 and 10 attached to the frame. The plates, as they move step by step along the run-way, finally arrive at the impression point under the impression head 11 carried by an arm 12 which, in the particular form of machine illustrated herein as exemplifying my invention, is pivotally mounted at 13 to the frame. The arm is normally raised by a spring 14 and it has a handle 15 by which it may be thrown downwardly to make the impression. The sprocket wheel 5 is mounted on a shaft 16, suitably journaled in the frame and projecting through the front wall of said frame and at a point at the left of the center of the machine, that is to the left of the plane of the impression point. This shaft is provided with a knob 17 which, when turned

by hand, will turn the shaft and thus the sprocket chain will be operated to feed the address plates from the hopper 1 by taking the lowermost plate in the pile and moving it along the run-way. In order that the operator may readily determine when a plate is in position at the impression point, I provide feeler means acting upon the feed mechanism which will give notice to the operator when the plate is positioned. This feeler means, in the particular machine shown, consists of a disk 18 fixed on the shaft 16 and having a plurality of notches 19 in its periphery, there being two in the present instance illustrated, these notches being adapted to receive a feeler roller 20 mounted on an arm 21, pivoted at 22 to a bracket 23 of the main frame. The arm 21 is pressed by a spring 24. When now the operator turns the handle 17 he continues the movement until he feels the action of the feeler roller dropping into one of the notches 19. When this occurs he knows that the feed chain has been moved sufficiently to position one of the plates exactly at the impression point. This relieves the operator of exercising the care that would be necessary were the feeler device omitted. When the roller 20 drops into the notch 19 additional force will be necessary in order to turn the knob over that which is necessary when the roller was simply bearing upon the periphery of the disk 18, and the operator will thus have positive notice when an address plate arrives in exact position at the impression point. The feed chain may be protected by a casing 25 attached to the frame and extending under the chain from end to end. The idler 4 may be mounted in a fork or arm 26 pressed by a spring 27, the fork sliding in a bearing 28.

The inking ribbon has its ends connected with spools 29, 30 mounted on a shaft 31, arranged adjacent the pivoted end of the impression arm and operated each time the impression arm rises by a pawl 32 pivoted on the impression arm and engaging a ratchet wheel 33 mounted on the shaft 31. From the spools the ribbon passes forwardly to a point over the run-way and then is turned about any suitable form of inclined guide at 34, which directs the ribbon lengthwise of the run-way at the impression point. The ribbon spools may have any suitable form of device for attaching them to or releasing them from the shaft 31 so that one will be fixed to wind the ribbon while the other is loose to unwind, and I have indicated generally in Fig. 1 clamping and releasing means at 35. Any suitable form of gage, as at 36, may be used for locating the articles to be addressed.

It will be seen that the inking ribbon is moved each time that the impression arm 65 is operated, and further that the impression

arm and the plate feed are operable independently of each other, so that the operator may take any desired number of impressions from the same address plate by simply allowing the plate feeding mechanism to remain inoperative, a fresh portion of the ribbon coming into use for each impression. Furthermore by the independent operation of the plate feeding mechanism, it will be possible for the operator to skip any desired plate without making an impression.

In order that the operator may read the plates readily as they leave the hopper, I may employ a mirror, as at 37, arranged in upright position adjacent the hopper and over the run-way, the reflecting surface being that marked 38, or a mirror may be arranged in rear of the runway at a point adjacent the hopper, as indicated at 39. These mirrors will enable the operator to read the plates, notwithstanding the fact that they may be placed in the machine out of position for reading from the front.

In machines in which the impression head is operated by hand there is a tendency with some operators for the impression head to rebound slightly and then deliver a second blow, resulting in a more or less blurred impression. In order to overcome this objection I provide a handle and impression arm of the form shown in Fig. 6, in which the impression arm 12* is arranged as a separate member from the hand lever 15*, but is operated therefrom. This impression arm is pivotally mounted at 13* and the hand lever 15* is also pivotally mounted at this point. A pin 40, fixed in the impression arm, passes through an elongated opening 41 formed in the hand lever. The hand lever is provided with a projection or lug 42 adapted to come against a portion of the main frame at 43 when the hand lever is thrown down. In this action the impression arm will be carried down but the hand lever will be arrested before the downward movement of the impression arm is completed. The impression arm, however, may complete its downward movement under the momentum given to it by the operation of the handle 15*, because the pin 40, which is fixed to the impression arm, is free to move in the elongated opening 41. The action therefore is that the hand lever will be arrested by the stop 42. The impression arm will, under its momentum, continue downward, this being allowed by the slot 41 and will, therefore, make the impression. It will be perfectly free to rebound but will not strike the second blow as it would do were the pressure of the hand applied directly thereto. The result is a clear and sharply defined print. The impression arm with this form of handle is raised by the spring which is supplied in any suitable

manner, such for instance as shown in Fig. 2. The impression arm, while shown of a slightly different shape from that shown in Fig. 2, and pivoted at a slightly different point, can be of the same shape substantially as that shown in Fig. 2 and it can be pivoted at the same point as illustrated in Fig. 2.

After leaving the impression point the printing or address plates are delivered to a receiver at the left of Figs. 1 and 3.

What I claim as my invention is

1. In an addressing machine, a table having a runway for individual printing plates, an impression arm, inking ribbon mechanism operating in unison therewith, and an address plate feeder consisting of an endless member having plate engaging means, said feeder moving the plates along the runway to and past the impression point, a rotary handle for operating the said member and a feeler device for determining the location of an address plate at the printing point.

2. In an addressing machine, a table having a runway for individual printing plates, an impression arm, inking ribbon mechanism operating in unison therewith, an endless member for feeding address plates, a drive wheel for said member, to operate the same to move the plates along the runway to and past the impression point, a shaft for the drive wheel extending to the front of the machine, a rotary handle on the shaft, and a feeler device consisting of a disk on the shaft having notches and a spring pressed

arm engaging said notches, substantially as 35 described.

3. In combination, an impression arm pivoted at its rear end and swinging downwardly and forwardly to make the impressions, an inking ribbon operated therefrom, and a plate feed for independent address plates consisting of an endless member having means to engage the plates, a drive wheel for the endless member and a shaft for the drive wheel, extending to the front of the machine and having a knob thereon for turning it, and a feeler device for determining the location of the independent address plates at the printing point, substantially as 45 described.

4. In combination a pivotally mounted impression arm, a pivotally mounted handle, said arm and handle turning about the same pivot, means for arresting the movement of the handle, a loose connection between the handle and the impression arm to allow the latter to continue its impression stroke after the handle is arrested, and spring means for raising the impression arm from the impression point, said spring means serving to lift 55 the handle also, substantially as described.

In testimony whereof, I affix my signature in presence of two witnesses.

ULYSSES GRANT LEE.
